Hayes, England

Application March 9, 1948, Serial No. 13,902
In Great Britain April 21, 1947

15 Claims. (Cl. 90—13.9)

1

This invention constitutes an improvement on or modification of the profile generating machine forming the subject of my application for Letters Patent Serial No. 710,600, filed November 18, 1946, according to which "work" is mounted relatively to a shaping or like tool so that movements of a tracer according to master form ordinates measured from a flat base will produce finished "work" having a profile similar to that of the master form but with the ordinates measured from a base of predetermined curvature, and for attaining the desired result the master form is reciprocated rectilinearly and the "work" is oscillated along a curved path.

According to the present invention the "work" is mounted on the opposing faces of face-plates arranged to be swung about an axis the inclination of which to the direction of length of the "work" may be adjusted.

For this purpose the "work" may be mounted on a carrier having trunnions at its opposite ends, the trunnion at one end being free to turn in a ball located in a spherical-bearing block attached adjustably to one of the face plates and the trunnion at the other end being carried in a bearing which is itself mounted to move, about an axis extending transversely of the axis of oscillation of the "work," relatively to a block attached adjustably to the other face plate, the adjustable attachments of the two blocks being such as to permit their distances from the centers of the face plates to be varied in parallel directions, similarly but oppositely.

The second mentioned block may be bifurcated and the bearing for the second mentioned trunnion may be carried by pintles extending, transversely of the axis of oscillation of the "work," through the limbs of the bifurcated block.

The two face plates may be secured to the limbs of a torsionally stiff U-shaped member mounted for oscillation on trunnions in bearings in a main head and a tail support, respectively, which are rigidly attached to an inclinable table pivoted by lugs on a support block adjustably mounted on the base of the machine, in order that the axis about which the "work" is to be oscillated may be set at any desired height and inclination, relatively to the flat base of the master form and the axis about which the arm carrying the tracer and the tool is caused to rise and fall by the passage of the master form beneath the tracer.

These adjustments for height and inclination of the inclinable table may be effected by forming the support block for said table with pairs of posts at its ends and symmetrically arranged

2

at its opposite sides, said posts having therein vertical slots through which pass shafts carrying gear wheels meshing with racks on the posts, one shaft passing also through lugs on the inclinable table and the other shaft passing also through lugs on a member slidable in relation to the length of said table, and each shaft carrying a worm wheel with which meshes a worm on a worm shaft rotatable in bearings in the inclinable table and in said slidable member, respectively.

In order that the inclinable table may be secured when it has been adjusted to the required height and inclination relatively to the base of the machine means are provided for clamping it to its support block. For example, the lugs on the inclinable table may be formed concentrically with undercut arcuate slots to receive the T-heads of bolts which pass through the vertical slots in the adjacent posts on the support block and the lugs on the slidable member may be formed with arcuate slots to give passage to bolts which pass also through the vertical slots in the other pair of posts on the support block, all said bolts having clamping nuts threaded thereon.

In order that twist may be produced in the "work" means may be provided for turning the "work" carrier progressively about the axis of its trunnions in addition to its oscillation about a curved path. For this purpose the "work" carrier may have attached coaxially, and preferably adjustably, thereto an arm cooperating with a cam arranged to co-operate, during the oscillation of the work, with a relatively fixed part of the machine, for instance, by means of a plate movable with the cam and inclined to the direction of oscillation of the "work," the inclined plate lying between a pair of rollers. The cam and the inclined plate may be adjustably mounted and at least one of the rollers may be mounted by means of an eccentric bush on a part arranged to be traversed concurrently with the traversing of the arm which carries the tracer and tool. Further co-operation of the arm with the cam may be ensured by hydraulic pressure acting on the arm.

The invention is illustrated by way of example in the accompanying drawings wherein:

Figure 1 is a general arrangement plan view of a machine;

Figure 2 is a general arrangement and elevation, from the left, Figure 1;

Figure 3 is an end elevation, from the right, Figure 1 showing only the base of the machine, the arm for carrying the shaping tool and the

tracer and undercut guideways for parts movable on the base;

Figures 4, 5 and 6 are enlarged detail views of the master form mounting, Figure 4 being an end view, from the left, Figure 1, Figure 5 a plan thereof and Figure 6 a section on the line VI—VI, Figure 5;

Figure 7 is an enlarged partly sectional side view, from the bottom, Figure 1, of the "work" mounting;

Figure 8 is a sectional elevation on the line VIII—VIII, Figure 7;

Figure 9 is an enlarged plan of the "work" mounting;

Figure 10 is a sectional elevation on the line X—X, Figure 9;

Figure 11 is a partly sectional end view of a detail;

Figures 12 and 13 are further enlarged detail sections on the lines XII—XII and XIII—XIII, Figure 9, respectively;

Figure 14 is an enlarged side elevation of adjustable means for an inclinable table to enable variation of the height and inclination of the "work" mounting shown in Figure 7;

Figure 15 is a fragmentary end view in the direction of the arrow XV, Figure 14;

Figure 16 is a similar view to Figure 7 but showing the "work" mounting in an alternative position.

Figures 17 to 22 are enlarged detail drawings:

Figure 17 being a side elevation of means for carrying the left-hand end, Figure 1, of the "work" mounting;

Figure 18 being a sectional plan on the line XVIII—XVIII, Figure 17;

Figure 19 being an end view from the left, Figure 17, parts being omitted for clarity;

Figure 20 being a plan of a bearing and parts associated therewith; and

Figures 21 and 22 being sections of parts on the lines XXI—XXI and XXII—XXII, Figure 19, respectively;

Figures 23 and 24 illustrate in greater detail the hydraulic connections of the jack shown in Figure 11:

Figure 23 being an elevation thereof and

Figure 24 being an elevation as seen from the left, Figure 23, parts being in central section.

As will be seen, especially in Figures 1, 2 and 3, the profiling of the work *e* is effected by an end milling cutter *j* and a rotary tracer *k* the axis and length of which are respectively perpendicular and parallel to the plane of the base line from which the ordinates of the master form *a* are measured, and the operative end of the milling cutter *j* and the contact point of the tracer *k* are located at said plane, the operative end of the tracer *k* consisting of a roller, the axis of which is parallel to that plane. If desired a ball or ball-ended stylus may be used as a tracer.

The milling cutter *j* and the rotary tracer *k* are carried by an arm *m* pivoted, at one end, on an axis *n*, *n* lying in said plane, in upstanding lugs 47, 47 on a carriage 48 slidable on a support 49 on a base 29, along which support 49 the carriage 48 may be traversed by a lead screw 50.

The master form *a* is mounted rigidly on a block *x* (see Figures 4, 5 and 6) on the upper part *y* of a rectilinearly reciprocating table *z*, the length of the master form *a* lying transversely of the direction of reciprocation of the table *z* and its chord (the base line from which its ordinates are measured) lying in a plane parallel with said direction. As shown on Figs. 4, 5 and 6, part *y*

is a mounting attached adjustably along the length of the reciprocating carriage *z* to carry transversely to the direction of reciprocation of carriage *z* the master form *a* on its mounting block *x* which is traversable along its length on the mounting piece *y*. The said mounting piece *y* carries also the ratchet 26 and gear wheels 22, 23, 24 and 25 by which the screw 21 is turned to cause traverse of the master form *a*. The part *y* may be attached at various positions along the length of the table *z* and the table *z* is mounted slidably on a support 11 and is reciprocated by means of a crank disc 12 carrying a crank pin 13 which extends into a block 14 slidable in a slot 15 presented by a pair of bars secured to the underside of the table *z*. The crank disc 12 is mounted on a vertical spindle 16 having thereon a worm wheel 17 driven by a worm 18 on a shaft 19 driven as explained hereinafter. In order that the length of travel of the table *z* may be adjusted to suit requirements the throw of the crank pin 13 may be varied by sliding a T-head on said pin in a transverse undercut slot in the crank disc 12 and clamping it in position in any suitable manner. In addition the block *x* is arranged to be traversed on the upper part *y* of the table *z* by means of a lead screw 21 driven through a train of gearing 22, 23, 24, 25 by a ratchet wheel 26, Figures 2 and 4, which is tripped, as the table *z* moves to the left, Figure 2, by a pawl 27 pivoted on a fixed bracket 28 on the base 29 of the machine. The ratio of this gearing may be varied by the substitution of other gear wheels to suit requirements, e. g. when rate of taper of the thickness of the "work," *e* along its length is different from that of the master form *a*. By these means different sections of the master form *a* may be presented under the tracer *k* in any position of the arm *m* along its support base 49. Alternatively, a drive by worm and change-speed gearing or cam may be provided for the continuous traversing of the master form *a* in order that when fast traversing of the arm *m* to a different position is required, the master form *a* may be moved to keep the required proportionate depth of the master form under the tracer *k* for each station along the "work."

As shown in Figures 1, 2 and 3, that end of the arm *m* remote from the axis *n*—*n* is restrained against lateral deflection by locating it, slidably up and down, between a pair of lugs 30, 30 on a carriage 31 slidable along a support 32 by means of a lead screw 33.

The tracer *k* is carried by a bracket 34 slidable along, and arranged to be clamped to, the arm *m* and the cutter *j* is mounted on a shaft 35 carried by the arm *m* in a bearing 36. The shaft 35 is driven by a belt 37 from an electric motor 38 mounted on the arm *m* above the pivotal axis *n*, *n* of said arm. Alternatively, a grinding wheel may be substituted to revolve about a vertical or an inclined axis.

The "work" *e* is also mounted on a carriage which, however, is not reciprocated rectilinearly but is oscillated along a curved path. For this purpose the "work" *e* is located in an open-topped trough shaped carrier 39 which has trunnions 40 and 41 at its opposite ends. The trunnion 40 is free to turn in a ball 42 mounted in a bearing block 43 which is attached adjustably to a face plate 44 so that its distance from the centre thereof may be varied. The face plate 44 is secured to one limb of a torsionally stiff U-shaped member 45 which may be oscillated about an axis 46—46, Figure 1 and 7, on trun-

nions 51 and 52, Figure 7, in bearings in a main head 53 and a tail support 54, respectively, which are rigidly attached to an inclinable table 55 pivoted by lugs 56 on a support block 57, Figures 2, 3 and 14, which is adjustably mounted on the base 29.

As shown, especially in Figures 17 to 22, the trunnion 41 of the carrier 39 is mounted in a bearing 58 which is itself mounted to move, about an axis 59—59. For this purpose the bearing 58 is carried by pinfles 60, 60 extending, transversely of the axis 59—59, through the limbs of a forked block 61 which, like the block 43, is attached adjustably to a face plate 62 (parallel with the face plate 44) so that its distance from the centre of the face plate 62 may be varied, and so that both blocks 43 and 61 may be adjusted in parallel directions, similarly.

In Figures 7, 9, 10 and 11 are shown means for oscillating the work mounting. From these figures it will be seen that beyond the main head 53 the trunnion 51 has an extension 63 on which a segment 64 is free to make a small angular movement about the axis 46—46, while on the trunnion 51 there is keyed one end of an arm 65 to the other end of which is pivoted the cylinder 66 of a hydraulic jack the piston rod 67 of which is pivoted to a lug 68 on the inclinable table 55. The segment 64 has projecting therefrom an arm 69 the free end of which is linked to the operating rod 70 of a hydraulic selector valve 71 for, and attached to the side of, the hydraulic cylinder 66.

The operative surface of the segment 64 is arcuate about the axis 46—46 and attached to the opposite ends of said arcuate surface are the ends of two flexible metal strips 72, 72 which extend oppositely over said surface and have their other ends attached to two arms 73, 73 in such manner that the strips 72, 72 are kept taut. The arms 73, 73 are fixed to the opposite end members 74, 74 of a carriage comprising the end members 74, 74 and two rods 75, 75, the rods 75, 75 being slidable horizontally in a support 76 extending upwardly from the base 29.

The left (Figures 1 and 9) of the support base 49, and as shown in section in Figure 10, constitutes a similar support base 77 on which a carriage 78 is mounted to slide in the same direction as the cutter mounting carriage 48, said carriage being coupled with the carriage 48 by a rod 79, the length of which is adjustable. The carriage 78 has therein a bearing for a vertical shaft 80 on the upper end of which is a disc 81 formed with a T-section transverse slot 82 in which is received the T-head of a crank pin 83 which may be located at any desired point along the length of the slot 82 and clamped in position by suitable means. The crank pin 83 projects into a block 84 slidable along a slot 85 (Figure 9) in a cross-carriage 86 which is slidable on the carriage 78 in a direction at right angles to the direction of movement of the carriage 78 on the support base 77. At the other end of the carriage 86 is secured a sleeved pin 87 (Figure 12) projecting into a block 88 slidable in half the depth of a longitudinal slot 89 in a thick lever 90. In the other half of the depth of this slot 89 is located another block 91 into which extends a pin 92 mounted on a bracket 93 on the end of the upper end member 74 of the carriage, see Figure 10. In another portion of the lever 90 (to the left, Figure 9) is a longitudinal slot 94 into which extend parts of a two-part block 95, Figure 13, other parts of which embrace said lever 90, the

parts being secured together by bolts 96, 96. Into the two-part block 95 extends a vertical fulcrum pin 97 about which the lever 90 is movable angularly, the fulcrum pin 97 being formed with a T-head 98 slidable in a correspondingly shaped slot in the main base 29 so that the fulcrum pin 97 may be adjusted relatively to the base 29 and then clamped in position by means of a lock nut 99.

10 By these means the pins 87 and 92 which project into the blocks 88 and 91 may be set, when required, at the same distance from the vertical fulcrum pin 97, hence rotation of the shaft 80 will cause the lever 90 to be oscillated in a horizontal plane about the vertical fulcrum pin 97 and thereby reciprocate the carriage 73, 75 and, through the metal strips 72, 72, cause the segment 64 to be oscillated and bring about oscillation of the "work" e about the axis 46—46.

15 The drive for the shaft 80 is derived from an electric motor 100 mounted on the main base 29, as shown at the left-hand side of Figure 1. The motor 100, through a gear box indicated generally at 101, drives two cross shafts 102 and 103, one, 102, of which has thereon a worm near each end and reciprocates the master form a through a worm wheel 104 on the shaft 19, and also drives the shaft 80 through a worm 105 (Figures 1 and 10), and a shaft 106, on a splined part of 30 which is a worm 105a meshing with a worm wheel 107 on the shaft 80. Thus the reciprocation of the master form a and the oscillation of the work e are effected in synchronism.

20 The shaft 103 also has thereon a worm near each end and effects the necessary traversing movements of the arm m at right angles to the direction of reciprocation of the master form a through a worm wheel 108 on the lead screw 33 for the carriage 31 and a worm wheel 109 on the lead screw 50 for the carriage 48. Further, as shown in Figures 1 and 2, the shaft 103 carries a worm 110 meshing with a worm wheel 111 on a lead screw shaft 112 for a purpose which will be explained hereinafter.

25 In order that the axis 46—46 about which the "work" e is oscillated may be set at any desired height and inclination, relatively to the flat base of the master form a and the axis n—n, about which the arm m is caused to rise and fall by the passage of the master form a beneath the tracer k, Figures 1 and 2, use is made of the means shown in Figures 14 and 15 for adjusting the inclinable table 55. In these Figures 14 and 15 it will be seen that the support block 57 has pairs 30 of posts 113, 113 and 114, 114 at its ends and symmetrically arranged at its opposite sides. The bottom of the support block 57 is horizontal and is slidable, as shown in Figure 3, on undercut guideways 115 on the main base 29 by means of a lead screw 116.

35 The posts 113, 113 and 114, 114 are formed with vertical slots 117 and 118 respectively and through each of these slots passes a shaft 119 carrying at each end a gear wheel 120 meshing with a rack 40 121 secured to the adjacent post 113 or 114 alongside a slot 117 or 118. One shaft 119 passes through the lugs 56 (Figure 7) on the inclinable table 55 and the other passes through similar lugs 122, 122 on a member 123 slidable in undercut guides 124, Figure 15, in relation to the length of the inclinable table 55. Each shaft 119 carries a worm wheel 125 with which meshes a worm 126 on a worm shaft 127 carried in bearings in one end of the inclinable table 55 and in the member 123, respectively. When the inclinable

table 55 has been adjusted by these means to the required height and inclination it is clamped to the posts 113, 113 and 114, 114, by bolts 128 passing through the slots 117 and 118, respectively. For this purpose the lugs 56 on the inclinable table 55 are formed concentrically with undercut arcuate slots such as 129, Figure 7, to receive T-heads of the bolts 128 associated therewith and the lugs 122 on the member 123 are formed with arcuate through slots such as 130, 10 Figure 14.

Figure 16, which is similar to Figure 7, shows the "work" mounting set in an alternative angular position by the means just described (but not illustrated in Figure 16) for shaping the reverse 15 face of the "work."

If the impression to be produced in the "work" is to be twisted in form it is mounted in the trough-shaped carrier 39 in such a position that the axis of twist of the shape to be produced coincides with the axis 131—131 about which the trunnions 40 and 41 turn.

As shown, especially in Figure 8, the carrier 39 has an arm 132 attached to it by bolts 133, Figure 18, the T-heads of which are received in a correspondingly undercut arcuate slot 134, Figure 8, having the axis 131—131 as its centre, so that the angular position of the arm 132 in relation to the carrier 39 may be adjusted. The arm 132 is formed with a slot 135 to constitute a guideway for a bearing block 136 into which extends a pin 137 projecting laterally from a bar 138 lying transversely of the arm 132. The bearing 58 for the trunnion 41 is integral with two upwardly extending lugs 139 and 140 (see also Figures 17, 19, 20, 21 and 22) which provide bearings in which the bar 138 is slidable, and it is also integral with two lugs 141 for clamping to the sides of the face plate 62 by means of T-headed bolts such as 142 fitting into correspondingly shaped slots such as 143 in the edges of said face plate. Further the bearing 58 has a lateral extension 144, Figures 19 and 21, carrying a guideway 145 for a carriage 146 so that movement of the carriage 146 is confined to a direction parallel to the axis 131—131. The extension 144 is a close fit on one of the pintles 60 to which it is secured by a nut 147, Figure 19. The angular position of the guideway 145 in relation to the bearing 58 is set by a lug 148, Figure 21, on the extension 144, which is secured by a bolt 149 to the adjacent lug 141. On the upper face of the carriage 146 is attached a cam plate 150 (Figures 1, 7, 8 and 16) against the face of which bears a roller 151 carried in bearings in the bifurcated end of the bar 138.

By means of a hydraulic jack 152 anchored pivotally to a bracket 153 extending from the lug 140 the angular position of the carrier 39 is held so as to keep the roller 151 in contact with the cam 150, the piston of the jack 152 being connected by its piston rod 154 with the arm 132, and fluid, at a predetermined pressure being supplied to the jack 152 (by a pump, not shown) through a flexible pipe 155, at that side of its piston to which the piston rod 154 is attached. Any seepage to the opposite side of the piston is led away by a flexible pipe 156.

Adjustably attached at one end of the carriage 146 (see Figure 7) in a plane inclined to the direction of movement of said carriage along the guideway 145 is a tongue 157 the opposite faces of which are accurately parallel and set so as to be at right angles to the axis 46—46, and bearing against these two faces, respectively, are two

rollers 160, 161 (see Figures 8 and 9) carried on axles 162, 163 mounted (e. g. on eccentric bushes) to rotate on one side of a carriage 164 slidable, in a direction parallel to and equally with or proportionately to, the movement of the cutter mounting carriage 48, on a guideway on a support 165 on the main base 29 by means of the lead screw 112 which is driven by the shaft 103 as mentioned above. Thus the traversing of the carriage 164 controls the angular position of the carrier 39.

The gear box 101 provides the desired variety of directions and speeds of rotation of the shafts 102 and 103 for the operations of cutting the die impression in the "work" e with the end milling cutter j, fast traversing in either direction to bring the cutter into position, and for finishing the die impression by grinding in longitudinal passes along the "work" e. For the last mentioned operation alternative means of rapid traversing of the carriages 48, 31 and 164, after disengagement of the lead screws 50, 33 and 112, may be provided by racks or linkages operated by pinions or cranks on the shaft 103.

Figures 23 and 24 show in greater detail the hydraulic jack 66, 67 illustrated generally in Figure 11. The valve 71 is a selector valve such as is described in the specification accompanying application for Letters Patent Serial No. 717,485 filed December 20, 1946, and now Patent No. 2,560,841, granted July 17, 1951. Immediately the operating rod 78 of said selector valve is displaced fluid under pressure from a pump (not shown) is led to said valve by a flexible pipe 166, passes to the cylinder 66 to the one side or the other of the piston 167, and causes the piston rod 67 to move in such a direction that the arm 65 turns the shaft 62 so that in angular travel it follows the segment 64 within exceedingly close limits. 40 168 is a flexible pipe for the exhaust from the cylinder 66.

I claim:

1. A profile generating machine comprising a master form, means for reciprocating the master form rectilinearly, a tracer movably mounted in relation to the master form, a cutting tool movable concurrently with the tracer, means for mounting a workpiece on the machine and for oscillating it along a curved path, whereby movements of the tracer according to master form ordinates measured from a flat base produce finished "work" having a profile similar to that of the master form but with the ordinates measured from a base of predetermined curvature, said base line lying transverse to the length of the work the means for mounting the workpiece comprising face plates connected together so as to prevent angular movement relative to one another, means for securing the workpiece obliquely to the opposing faces of said face plates, and means for swinging said face plates about an axis the inclination of which to the direction of length of the workpiece may be adjusted.

2. A profile generating machine comprising a master form, means for reciprocating the master form rectilinearly, a tracer movably mounted in relation to the master form, a cutting tool movable concurrently with the tracer, means for mounting a workpiece on the machine and for oscillating it along a curved path, whereby movements of the tracer according to master form ordinates measured from a flat base produce finished "work" having a profile similar to that of the master form but with the ordinates measured from a base of predetermined curvature, the

means for mounting the workpiece comprising face plates, means for securing the workpiece to the opposing faces of said face plates comprising a carrier, trunnions at the opposite ends of the carrier, a spherical bearing block attached adjustably to one of said face plates, a ball located in the spherical bearing and formed with a socket to receive the trunnion at one end of the carrier, and a second block attached adjustably to the other of said face plates, a bearing mounted to move relatively to said block about an axis extending transversely of the axis of oscillation of the workpiece, said bearing receiving the trunnion at the other end of the carrier, the attachments of the two blocks permitting their distances from the centres of the face plates to be varied in parallel directions, similarly but oppositely.

3. A profile generating machine comprising a master form, means for reciprocating the master form rectilinearly, a tracer movably mounted in relation to the master form, a cutting tool movable concurrently with the tracer, means for mounting a workpiece on the machine and for oscillating it along a curved path, whereby movements of the tracer according to master form ordinates measured from a flat base produce finished "work" having a profile similar to that of the master form but with the ordinates measured from a base of predetermined curvature, the means for mounting the workpiece comprising face plates, means for securing the workpiece to the opposing faces of said face plates comprising a carrier, trunnions at the opposite ends of the carrier, a spherical bearing block attached adjustably to one of said face plates, a ball located in the spherical bearing and formed with a socket to receive the trunnion at one end of the carrier, and a second block attached adjustably to the other of said face plates, said second block having bifurcated limbs, a bearing, pintles on said bearing extending transversely of the axis of oscillation of the workpiece, through the limbs of the bifurcated block, said bearing receiving the trunnion at the other end of the carrier, the attachments of the two blocks permitting their distances from the centres of the face plates to be varied in parallel directions, similarly but oppositely.

4. A profile generating machine as claimed in claim 2, including a support block mounted on the machine, lugs on the support block, an inclinable table pivoted on said lugs, a main head and a tail support, the main head and the tail support being rigidly attached to the inclinable table, and being formed with bearings, trunnions oscillatable in the last mentioned bearings, and a torsionally stiff U-shaped member mounted on the oscillatable bearings, the face plates being secured to the limbs of the torsionally stiff U-shaped member.

5. A profile generating machine as claimed in claim 2, including a support block mounted on the machine, lugs on the support block, an inclinable table pivoted on said lugs, a main head and a tail support, the main head and the tail support being rigidly attached to the inclinable table, and being formed with bearings, trunnions oscillatable in the last mentioned bearings, a torsionally stiff U-shaped member mounted on the oscillatable bearings, the face plates being secured to the limbs of the torsionally stiff U-shaped member, pairs of posts symmetrically arranged at opposite sides of the support block and formed with vertical slots, shafts passing through

the vertical slots, gear wheels on said shafts, racks on the posts with which the gear wheels mesh, lugs on the inclinable table through which one of said shafts passes, a member slidably in relation to the length of the inclinable table, lugs on the slidable member, through which last mentioned lugs the other shaft passes, worm wheels on said shafts, respectively, worms with which said worm wheels mesh, said worm wheels being rotatable in bearings in the inclinable table and in the slidable member, respectively.

6. A profile generating machine as claimed in claim 2, including a support block mounted on the machine, lugs on the support block, an inclinable table pivoted on said lugs, a main head and a tail support, the main head and the tail support being rigidly attached to the inclinable table, and being formed with bearings, trunnions oscillatable in the last mentioned bearings, a torsionally stiff U-shaped member mounted on the oscillatable bearings, the face plates being secured to the limbs of the torsionally stiff U-shaped member, pairs of posts symmetrically arranged at opposite sides of the support block and formed with vertical slots, shafts passing through the vertical slots, gear wheels on said shafts, racks on the posts with which the gear wheels mesh, lugs on the inclinable table through which one of said shafts passes, a member slidably in relation to the length of the inclinable table, lugs on the slidable member, through which last mentioned lugs the other shaft passes, worm wheels on said shafts, respectively, worms with which said worm wheels mesh, said worm wheels being rotatable in bearings in the inclinable table and in the slidable member, respectively, and means for clamping the inclinable table to the posts after said table has been adjusted to the required height and inclination relatively to the base of the machine.

7. A profile generating machine as claimed in claim 2, having means for turning the workpiece carrier progressively about the axis of its trunnions in addition to its oscillation about a curved path, in order that twist may be produced in the "work."

8. A profile generating machine as claimed in claim 2, including an arm attached coaxially to the carrier, a cam co-operating with said arm, means for oscillating said arm and said cam as one with the workpiece, the cam being arranged to co-operate with a relatively fixed part of the machine and cause it to move said arm and, consequently, the carrier about the axis of the carrier trunnions during the oscillation of the workpiece.

9. A profile generating machine as claimed in claim 2, including an arm attached coaxially to the carrier, a cam co-operating with said arm, means for oscillating said arm and said cam as one with the workpiece, the cam being arranged to co-operate with a relatively fixed part of the machine by means of a plate movable therewith and inclined to the direction of oscillation of the workpiece, and a pair of rollers on a second relatively fixed part of the machine, the inclined plate lying between said rollers.

10. A profile generating machine as claimed in claim 2, including an arm attached coaxially to the carrier, a cam co-operating with said arm, means for oscillating said arm and said cam as one with the workpiece, the cam being arranged to co-operate with a relatively fixed part of the machine by means of a plate movable therewith and inclined to the direction of oscillation of the

11

workpiece, and a pair of rollers on a second relatively fixed part of the machine, and means for traversing said second relatively fixed part of the machine concurrently with the traversing of the arm which carries the tracer and the tool, the inclined plate lying between said rollers.

11. A profile generating machine as claimed in claim 2, including an arm attached coaxially to the carrier, a cam co-operating with said arm, means for oscillating said arm and said cam as one with the workpiece, the cam being arranged to co-operate with a relatively fixed part of the machine and cause it to move said arm and, consequently, the carrier about the axis of the carrier trunnions during the oscillation of the workpiece, a rod slidable transversely of the arm attached to the carrier, a roller at one end of said rod, hydraulic means keeping said roller in contact with the cam, and guides integral with the bearing which is mounted to move, about an axis extending transversely of the axis of oscillation of the workpiece, relatively to a block on a face plate, said rod being slidable in the guides.

12. A profile generating machine as claimed in claim 2, including an arm attached coaxially to the carrier, a cam co-operating with said arm, means for oscillating said arm and said cam as one with the workpiece, the cam being arranged to co-operate with a relatively fixed part of the machine and cause it to move said arm and, consequently, the carrier about the axis of the carrier trunnions during the oscillation of the workpiece, a rod slidable transversely of the arm attached to the carrier, a roller at one end of said rod, hydraulic means keeping said roller in contact with the cam, guides integral with the bearing which is mounted to move, about an axis extending transversely of the axis of oscillation of the workpiece, relatively to a block on a face plate, said rod being slidable in the guides, the hydraulic means consisting of a hydraulic jack, a bracket integral with the guides, the hydraulic jack being anchored pivotally on the bracket, the jack having a piston rod pivoted to the free end of the arm and means for supplying fluid at a predetermined pressure to the jack.

13. A profile generating machine as claimed in claim 2, including an arm attached coaxially to the carrier, a cam co-operating with said arm,

12

means for oscillating said arm and said cam as one with the workpiece, the cam being arranged to co-operate with a relatively fixed part of the machine and cause it to move said arm and, consequently, the carrier about the axis of the carrier trunnions during the oscillation of the workpiece, the cam being mounted adjustably so that its co-operation with the arm may be varied according to the degree of twist to be produced in the work.

14. A profile generating machine as claimed in claim 2, including an arm attached coaxially to the carrier, a cam co-operating with said arm, means for oscillating said arm and said cam as one with the workpiece, the cam being arranged to co-operate with a relatively fixed part of the machine by means of a plate movable therewith and inclined to the direction of oscillation of the workpiece, and a pair of rollers on a second relatively fixed part of the machine, the inclined plate lying between said rollers and being mounted adjustably so that its co-operation with the cam may be varied, according to requirements.

15. A profile generating machine as claimed in claim 2, including an arm attached coaxially to the carrier, a cam co-operating with said arm, means for oscillating said arm and said cam as one with the workpiece, the cam being arranged to co-operate with a relatively fixed part of the machine by means of a plate movable therewith and inclined to the direction of oscillation of the workpiece, and a pair of rollers on a second relatively fixed part of the machine, the inclined plate lying between said rollers, at least one of the rollers being mounted by means of an eccentric bush.
